UNITED STATES PATENT OFFICE

JOHN LEECH, OF BRIDGEPORT, CONNECTICUT, ASSIGNOR TO INTERNATIONAL SILVER COMPANY, OF MERIDEN, CONNECTICUT, A CORPORATION OF NEW JERSEY

DESIGN FOR A SPOON, KNIFE, FORK, OR OTHER ARTICLE OF FLATWARE

Application filed March 11, 1932. Serial No. 43,153. Term of patent 7 years.

To all whom it may concern:

Be it known that I, JOHN LEECH, a citizen of the United States, residing at Bridgeport, county of Fairfield, and State of Connecticut, have invented a new, original, and ornamental Design for a Spoon, Knife, Fork, or Other Article of Flatware, of which the following is a specification, reference being had to the accompanying drawings, forming a part thereof.

Fig. 1 is a front elevation of a spoon showing my new design; and

Fig. 2 is a cross-sectional view near the middle of the spoon handle.

The back of the spoon conforms with the disclosure in Fig. 2, and may be plain or have surface ornamentation embodying the motif disclosed in Fig. 1.

I claim:

The ornamental design for a spoon, knife, fork or other article of flat-ware, substantially as shown and described.

JOHN LEECH.
